UNITED STATES PATENT OFFICE

2,094,485

PROCESS FOR SWEETENING HYDROCARBON FLUIDS

Albert E. Buell, Bartlesville, Okla., assignor to
 Phillips Petroleum Company, a corporation of
 Delaware

No Drawing. Application January 22, 1937,
 Serial No. 121,908

8 Claims. (Cl. 196—29)

This application is a continuation in part of my copending application, Serial No. 725,405, filed May 12, 1934.

This invention relates to the refining of hydrocarbon products and particularly to the refining of petroleum products containing malodorous sulfur compounds of the mercaptan type. More directly, it relates to sweetening "sour" petroleum hydrocarbon products by means of a moist solid reagent comprising copper chloride adsorbed on carriers. The invention is of special value and application in the treatment of light petroleum distillates such as natural gasoline, refinery straight run and cracked gasolines, petroleum solvent naphthas, liquefied petroleum gases, and the like.

Such unrefined petroleum products contain mercaptans, commonly called "sour" elements, which give the oil undesirable odor, and render it corrosive and unstable. These compounds are customarily removed, or altered, by the so-called "doctor" process, a laborious, cumbersome and very uneconomical chemical treatment with alkali plumbite and sulfur. In some instances, e. g., natural gasoline, the sweetening reaction has been accomplished through the use of alkaline hypochlorite solutions, but this method, too, has not proved satisfactory in most cases. Sometimes the "sour" elements seem to be particularly difficult to sweeten, thereby requiring large quantities of the reagent, and in other cases the treatment seems to result in the introduction into the oil of undesirable constituents as bad as those originally present. Still other methods have been suggested for removal or conversion of the mercaptans but almost without exception these methods involve numerous treating steps which demand such close control of the operation that the operating costs are increased so much as to render such methods uneconomical.

One of the principal objects of the present invention is to provide a process for sweetening the mercaptan-bearing oils in a far more efficient and inexpensive manner than practiced heretofore.

Another object of the invention is to provide a process for converting the mercaptans in the oil to the disulfide form without the production of and the consequent introduction into the oil of the various undesirable compounds which are formed as by-products in nearly all of the sweetening methods used heretofore.

Still another object of the invention is to provide a process wherein the sweetening reagent is regenerated either continuously or intermittently.

A further object of the invention is to provide a process and reagent which is so rapid in its sweetening reaction that the apparatus necessary for this refining step is very small and inexpensive as compared to that needed for any of the methods suggested heretofore.

Other objects and novel features and advantages of this invention will be apparent from the following specification.

I have discovered that a solid treating agent comprising a highly porous or adsorbent material such as fuller's earth, charcoal and the like, impregnated with a concentrated solution of cupric chloride, is an excellent reagent for rapidly and efficiently sweetening "sour" hydrocarbon oils. I have found that during simple filtering of the oils in the liquid state at ordinary temperatures through a bed of this reagent the mercaptans are converted to the disulfides. The principal reactions are believed to be shown in the equations:

In the first step of the reaction, one-half of the mercaptan is converted to the alkyl disulfide and the rest is left as cuprous mercaptide. The latter then reacts (as shown in Equation 2) with additional cupric chloride to give alkyl disulfide and cuprous chloride. On combining the two equations into one, the ultimate reaction is:

Since cuprous chloride and hydrochloric acid are formed in the reaction at the expense of the cupric chloride, the reagent will gradually lose its activity and finally become spent, as the amount of mercaptan sulfur in the oil passed thru the reagent becomes more nearly equivalent to the cupric chloride used on the reagent. When the gasoline or oil contains only a very small quantity of mercaptan sulfur the life of the reagent is comparatively long, but when the mer-

captan content is high the life of the reagent is quite short.

I have discovered that this spending of the reagent can be prevented and the activity maintained over long periods even when treating gasolines of extremely high mercaptan content, e. g., those of west Texas origin, by dissolving air or an equivalent gas containing free oxygen in the gasoline previous to its passage thru the reagent bed. In this manner the cuprous chloride and hydrochloric acid, formed as shown above in the sweetening step, react with the oxygen in the air to give cupric chloride and water.

The cupric chloride is thus regenerated continuously in situ and the reagent remains in a highly active state over long periods of time during 20 which many equivalents of mercaptan sulfur are sweetened by one equivalent of cupric chloride.

The amount of air required depends, of course, on the mercaptan content of the sour product. Theoretically only 8 volumes of air (gas) at 0° C. and 750 mm. is required for 100 liquid volumes of gasoline containing 0.01% mercaptan sulfur. The quantity of air needed for the west Texas gasolines, some of which contain as high as 0.04% 30 mercaptan sulfur, is still quite low. I have found by experiment both in laboratory and in plant operations that a sufficient quantity of air can be dissolved in the gasoline under the usual conditions of plant operation to keep a cupric chloride-fuller's earth reagent regenerated. No loss 35 of oil vapors is encountered in this regenerative process inasmuch as the quantity of air needed is so small as to cause no appreciable increase in the vapor pressure of the product during treatment. Any gas containing free oxygen and not 40 detrimental to the copper treating reagent, may be used in conjunction with the hydrocarbon fluid so as to maintain the reagent in an active state.

For while it is possible to prepare the reagent 45 in any one of a number of ways, a preferred way is to spray a concentrated solution containing cupric chloride onto the solid adsorbent material used for the carrier, thereby impregnating the adsorbent with an aqueous solution phase containing cupric ions and chloride ions. Fuller's earth is preferred as the solid adsorbent carrier material, but other materials such as charcoal, 50 silica gel, alumina, pumice, etc., are suitable. It is understood, of course, that the cupric chloride 55 solution may be prepared not only from the salt itself, but also from other soluble copper salts with suitable soluble alkaline chlorides; copper sulphate and sodium chloride, for example, are a preferred combination. By the term "aqueous 60 solution phase" I mean to imply that the interstices or pores of the adsorbent are partly or completely filled with an aqueous solution containing copper chloride; obviously the quantity depends on the nature of the selected adsorbent, 65 but, for example, with fuller's earth a preferred quantity of solution lies within the range which will produce a content of 5 to 10% CuCl_2 in the finished reagent.

It is evident that the best sweetening results 70 can be obtained by having a relatively large volume of a comparatively concentrated solution adsorbed in the carrier. However, in order to apply the solution uniformly to the carrier it is usually desirable to use a somewhat more dilute 75 solution than that desired in the finished reagent.

and to subsequently remove a portion of the water of solution from the impregnated adsorbent, thus concentrating the solution after it has been adsorbed; but, if desired, the volume and concentration of the solution used for impregnation of a unit quantity of adsorbent may be controlled to give a finished reagent of the desired composition without removal or addition of water to it before use.

In the operation of the process as stated, hydrogen sulfide if present is removed by any desired means from the sour gasoline before treatment with the above described sweetening reagent. The requisite quantity of air is then dissolved in the gasoline, preferably using some excess air over the theoretical amount to take care of normal fluctuations in operation. The air may be added to the stream of sour gasoline flowing to the treater in any suitable manner; the amount may be automatically controlled in proportion to the flow of gasoline if desired, and the air may be introduced thru a porous tube or plate to break it up into small bubbles to insure rapid solution. The gasoline is then contacted with the reagent, preferably by filtration thru a bed disposed in a suitable closed treating vessel. Flow rates of 10-20 volumes of gasoline per hour per volume of reagent are generally satisfactory, but higher or lower rates may be used, depending mainly on the mercaptan content of the gasoline or other 20 hydrocarbon fluid treated.

Under normal conditions of continuous use the reagent has an indefinitely long life, averaging from six to twelve months, or longer. The principal change tending to occur is in the water 35 content. In some instances this is due to accumulation of water of reaction, or removal of water present in the gasoline by the reagent, resulting in dilution of the solution with which the carrier is impregnated. In other cases the gasoline 40 being treated may contain little or no dissolved water, particularly where it has been previously carefully fractionated for removal of excessively volatile hydrocarbons such as propane, and water is removed from the reagent by the gasoline, thus 45 tending to destroy the aqueous solution phase. Since it is evident that the amount of solution which can be adsorbed tightly enough on the carrier to be retained during passage of the gasoline is limited, and because the presence of enough 50 water to maintain the aqueous solution phase is highly essential it is necessary to take the proper steps, as outlined below, to maintain the volume and concentration of the solution within these limits.

Where, after a considerable period of operation, the reagent has accumulated water beyond that originally present, the reagent may be restored to substantially its original effectiveness by removal of the accumulated excess water; 60 this may be done, for example, by blowing the reagent bed with air, preferably heated to 150° F. or so; or by removing the reagent from the treating vessel and then removing the excess moisture. Under no circumstances, however, 65 should the water be removed to a point where the aqueous solution phase is destroyed, for it is essential to the conduct of the process covered by this application that an aqueous phase containing cupric ions and chloride ions be maintained 70 on the carrier, since without it the acid formed in the first step of the reaction (Equation 1) is not held by the reagent, and thus it cannot be regenerated, and the treated oil will contain acid and the very objectionable copper mercaptide. 75

By removing accumulated water at intervals, and taking the necessary precautions to prevent introduction of water into the reagent by the gasoline, other than reaction water, the life of the sweetening agent may be considerably prolonged.

Where the tendency is toward the reverse condition, that is, removal of water from the reagent by gasoline which is not saturated with water, the aqueous phase may be maintained on the carrier by adding water to the gasoline before treatment, so that the added water plus that formed in the reaction will balance the water content of the treated gasoline. One convenient way of accomplishing this is by introduction of a controlled small quantity of steam into the sour gasoline; the condensed steam is thoroughly dispersed and dissolved. In some cases the reagent life has been prolonged in this way to an indefinite period, compared with a period of only a few days without the addition of moisture before the reagent became dehydrated to the extent that the sweetening and regenerating reactions would not proceed.

In either case, therefore, whether the reagent tends to accumulate or to lose water, the life may be greatly prolonged by maintaining the aqueous solution phase with which the adsorbent is impregnated within the limits specified; in most cases, however, normal conditions are such that the solution concentration remains at substantially its original value, and the reagent requires attention only at infrequent intervals, as illustrated by the following examples:

Example I

A very sour west Texas gasoline, containing about 0.05% mercaptan sulfur, is treated by adding air and then passing it thru a bed of about 2,000 pounds of sweetening reagent at a flow rate of about 15,000 gallons per day. At approximately 100 day intervals accumulated water is removed from the reagent by taking the reagent out of the treating vessel and exposing it to the atmosphere until the water content is reduced to the original value. Meanwhile, a second treater is used to sweeten the gasoline. This reserve treater contains only 185 pounds of sweetening reagent, but can be operated at the 15,000 gallon flow rate for 30 day periods, if desired, before it accumulates sufficient excess water to prevent sweetening. The reagent was originally prepared by spraying 15-30 mesh fuller's earth with solution containing copper chloride prepared from copper sulfate and an excess of sodium chloride, to produce a reagent comprising about 75 parts by weight fuller's earth, and about 25 parts solution containing about 14% copper and 20% chloride ions.

Example II

A sweetening reagent was prepared by uniformly spraying each 1,000 pounds of 15-30 mesh fuller's earth with about 40 gallons of a solution containing about 10% chloride and about 7% cupric copper, made from copper sulfate and sodium chloride, and then concentrating the adsorbed solution to about 15% chloride content. The reagent was then used to treat a Mid-Continent gasoline with a low mercaptan sulfur content at a flow rate of about five volumes of gasoline per volume of reagent per hour, air in the proper proportion being added to the gasoline stream entering the treater. The gaso-
line was stabilized before treating to remove nor-

mally gaseous hydrocarbons and was substantially dehydrated by this fractionation. The dry gasoline removed water from the sweetening reagent to such an extent that complete sweetening was not obtained after several days operation. Steam was then added to the gasoline stream before treatment to replace the water removed from the adsorbed solution phase; the product became completely sweet. Thereafter a controlled amount of steam was continually added to the gasoline to maintain the solution at substantially its original concentration, and the reagent has continued to be used since. During the first year of operation about 80 million gallons of gasoline were treated, with 19,000 pounds of reagent present in the treater.

Example III

160 gallons of reagent prepared as in Example II was used to sweeten 10,000 gallons daily of north central Texas natural gasoline for a period of sixteen months. Normal conditions of operation were such as to maintain the solution adsorbed in the carrier at approximately its original concentration, during this period, without addition or removal of water from the reagent by the means described in the above examples. Cost of the chemicals used in preparation of the reagent amounted to about 6 mills per 1,000 gallons of gasoline treated during this period, compared with an average of about 16 cents per 1,000 gallons by the method formerly used.

What I claim and desire to secure by Letters Patent is:

1. A process for sweetening mercaptan-bearing hydrocarbon oil, comprising contacting said oil, in admixture with a gas containing free oxygen, with an adsorbent material impregnated with a maintained aqueous solution phase containing cupric ions and chloride ions.

2. A process for sweetening mercaptan-bearing petroleum oil, comprising contacting said oil, in admixture with air, with an adsorbent material impregnated with a maintained aqueous solution phase containing cupric ions and chloride ions.

3. A process for sweetening mercaptan-bearing petroleum oil, comprising adding air to said petroleum oil, and contacting the mixture of said oil and air with a sweetening agent consisting of an adsorbent material impregnated with a maintained aqueous solution of a soluble copper salt and a soluble chloride, whereby the said petroleum oil is sweetened and the sweetening agent is maintained active.

4. A process for sweetening mercaptan-bearing gasoline, comprising contacting said gasoline, in the presence of a small proportion of air, with a sweetening agent consisting of an adsorbent material impregnated with a maintained aqueous solution of a soluble copper salt and a soluble chloride, whereby the said gasoline is sweetened and the sweetening agent is maintained active.

5. A process for sweetening mercaptan-bearing petroleum oil, comprising adding air to said oil, and percolating the mixture of oil and air through a body of sweetening agent consisting of an adsorbent material impregnated with a maintained aqueous solution of a soluble copper salt and a soluble chloride, whereby the said petroleum oil is sweetened and the sweetening agent is maintained active.

6. A process for sweetening mercaptan-bearing gasoline, comprising adding air to said gasoline, and percolating the mixture of gasoline and air

through a body of sweetening agent consisting of fuller's earth impregnated with a maintained aqueous solution of a soluble copper salt and a soluble chloride, whereby the said gasoline is sweetened and the sweetening agent is maintained active.

5 7. A process as in claim 3 in which the soluble copper salt is copper sulfate and the soluble chloride is sodium chloride.

8. A process for sweetening mercaptan-bearing petroleum oil, comprising adding air to said petroleum oil, and contacting the mixture of said oil and air with a sweetening agent consisting of an adsorbent material impregnated with a maintained aqueous solution of cupric chloride, whereby the said petroleum oil is sweetened and the sweetening agent is maintained active.

5

ALBERT E. BUELL.
